UNITED STATES PATENT OFFICE.

CHARLES F. BRUSH, OF CLEVELAND, OHIO.

APPARATUS FOR MANIPULATING MOLDS IN CASTING.

SPECIFICATION forming part of Letters Patent No. 293,711, dated February 19, 1884.

Application filed October 24, 1883. (No model.)

To all whom it may concern:

Be it known that I, CHARLES F. BRUSH, a citizen of the United States, residing at Cleveland, county of Cuyahoga, State of Ohio, have 5 invented or discovered a new and useful Improvement in Apparatus for Manipulating Molds in Casting; and I do hereby declare the following to be a full, clear, concise, and exact description thereof, reference being had to the 10 accompanying drawings, making a part of this specification, in which—like letters indicating like parts—

Figure 1 is a side elevation of my apparatus, showing its position in lifting the mold from or depositing it on a mold-supporting table. Fig. 2, Sheet 2, is a side elevation of my apparatus having a mold attached thereto and suspended over a bath of molten metal. Fig. 3, Sheet 2, is an enlarged view, showing the 20 standard and its connections on which the operating-lever is mounted. Figs. 4, 5, and 6, Sheet 3, are enlarged detail views of the clutch mechanism used in lifting, opening, and closing the mold, and show said clutch in different operative positions. Fig. 7 is a detail 25 view of one-half of the clutch mechanism, the supporting-arm being shown in section.

My invention relates to an apparatus for effecting the various manipulations to which a 30 mold is subjected in carrying out the various steps of my improved process, which consists, in general terms, in immersing a hinged or jointed mold while tightly closed in a bath of molten metal, separating the parts of the mold, so as to admit the molten metal, closing the 35 mold while submerged, and then withdrawing the mold, all as more fully set forth in another application. After the mold is withdrawn from the bath, it is deposited on a suitable 40 table disengaged from the clutch mechanism, so that it can be opened and the casting withdrawn.

My invention consists in the construction and combination of devices or mechanism, 45 all as more fully hereinafter described and claimed.

The lever A is pivoted on a pin, a, mounted at its ends in the arms a' of a swinging frame, A', the lever being held centrally within this 50 frame by flanged collars a², surrounding the pivot-pin a, and arranged on each side of the

lever and between the arms a' of the swinging frame. This frame A' is pivoted at the end opposite the lever to the upper ends of the arms of the forked frame A² by a rod, a³; and this forked frame is vertically pivoted by its pin a⁴ on the end of the standard A³, so as to rotate on said pivot. By this construction I am enabled not only to move the lever vertically up and down, but also to swing it back 55 and forth longitudinally of itself, and to turn it around longitudinally, the purposes of such movements being hereinafter stated.

To the forward end, a⁵, of the lever A is attached a rod or bar, a⁶, projecting upward and 60 backward from the end a⁵; and upon this rod a⁶ is adjustably secured, by a collar and set-screw, a⁸, the weight or weights a⁷. To hold this rod a⁶ in proper position with relation to the pivot of the lever, brace-rods a⁹ and a¹⁰ are 65 secured to the lever A back of the pivot, and support the rod a⁶ at the middle and end thereof. The function of the weight will be stated hereinafter.

To the lever A, on each side of its pivotal 70 point, are attached one or more stops, a¹¹, which, by abutting against the standard A³, prevent too great a vertical movement of the lever.

On the under side of the lever, and forward 75 of its pivotal point, is attached a hook, a¹², and to this hook the weight a¹³, which is provided at its top with a swiveling stirrup, a¹⁴, is to be attached at certain times during the manipulation of the lever, for a purpose to be 80 hereinafter set forth.

Near the forward end of the lever, and on one side thereof, is attached a friction-roller, a¹⁵, which runs in a slotted standard, c, secured to the top of the furnace C, containing the bath 90 of molten metal.

To the extreme forward end of the lever A is pivoted, by a pin, a¹⁶, the supporting-arm b, which is provided with ears b', extending upward on each side of the end of the lever, and through which passes the pivot-pin a¹⁶. These ears b' form broad bearing-faces, and thereby prevent any sidewise oscillation of the arm b and the parts connected thereto. Near its lower end this arm b is provided with two 95 horizontal slots, b², through which pass the pins b³, which also pass through the lugs b' of

the cylindrical pieces of metal b^5 , and serve as pivots therefor. The adjacent ends of these lugs are curved to form cam-surfaces, for a purpose hereinafter stated. The curvature of these cam-surfaces is determined by the arc of a circle whose center is located at the center of a knob or projection, b^{12} , on the periphery of the block b^5 .

In the cylindrical blocks b^5 are formed V -shaped radial slots b^6 , into which pass the handles b^7 of the two parts E' of a flask, E , and these handles are locked and held within these radial slots by bell-crank levers t^8 , one on each end of the blocks b^5 , which are provided with hooks at one end to catch under the handles b^7 when they enter the slots b^6 . The outer ends of each pair of levers b^8 are united together by a bar, b^9 , thereby insuring a simultaneous movement of the hooks at each end 20 of the blocks.

To the arm b , above the slots b^2 , are pivoted the dogs b^{10} , which are provided with hooks b^{11} at the inner side of their outer ends. These hooks b^{11} , at a certain point in the operation of this device, catch into grooves e , which may be formed in the outside walls of the mold, or in a plate secured on the outer sides of the mold, and at the top thereof, and thereby hold the parts of the mold together and furnish a means for lifting the mold from the bath. These dogs b are held in operative positions, and are operated by a spring, s .

The operation of my device is as follows, and in this description I will start with the mold in a closed condition and resting on the stand D , Fig. 1, located in convenient proximity to the furnace C , and within the sweep of the forward end of lever A : The mold being closed and in an upright position, a workman raises the handle end h of the lever A , thereby lowering the end a^6 of the lever, and with it the blocks b^5 , into the slots b^6 of which pass the handles b^7 of the mold. In entering these slots the handles b^7 strike and push aside the hooked ends of the bell-crank levers b^8 , and when the handles b^7 have reached the bottom of the radial slots b^6 the hooked ends of the levers b^8 will drop back into place under the handles b^7 and securely lock them in the slots, as shown in Fig. 4. After the mold has been securely caught in the blocks b^5 , the swivel-stirrup a^{14} of the previously-attached weight a^{13} is turned to disengage it from the hook a^{12} on the lever A , the sole function of this weight a^{13} being to counterbalance the weight a^7 when the mold is not attached to the lever, and for this purpose it is to be hooked onto the lever when the mold is disengaged from the lever and is to be unhooked, as just stated, when the lever and mold are again connected. When the handle end h of the lever A is near or below a horizontal plane passing through the pivot a , the weight a^7 acts on the handle side of the pivot. The mold having been secured in the blocks b^5 , and the weight a^7 having been disengaged from the lever A , the workman depresses the

end h of the lever A , thereby lifting the mold from the stand D , and swings the mold around, by turning the lever A on its vertical pivot a^4 in the standard A , over the furnace C . During this movement the weight of the mold is counterbalanced wholly or in part by the weight a^7 , and the mold is held closed by its own weight, as the handles b^7 of the mold are farther apart than the distance between the slots b^6 in the blocks b^5 when said blocks are hanging loose and disengaged from the handles of the mold B , for it will be observed that the blocks b^5 have a limited range of downward-swinging motion on the pivot-pins b^3 , so that the two parts of the mold will be closed together before the contiguous eccentric or cam faces of lugs b^4 come in contact; but it should also be added that when this clutch and lifting mechanism is disengaged from the mold, so that such eccentric faces may come in contact with each other, such contact will take place before the open ends of the slots b^6 pass out of proper position to slip readily onto the handles b^7 , as above described. The feature last referred to, however, is not necessary, provided other means be employed, manual or otherwise, for guiding the slots b^6 onto the handles b^7 . The outer end, h , of the lever A is now raised, care being taken to guide the friction-roller a^{15} into the slot in the standard c on the furnace, and as this friction-roller a^{15} moves down the nearly vertical slot in c it causes the lever A to swing backward slightly on the pivot a^3 of the swinging frame A' , and consequently the mold descends into the bath in a practically straight line of motion. As the lever A approaches a horizontal position the weight a^7 acts more nearly in the vertical line of the pivot a , and when this lever has reached such a position that the bottom of the mold is about entering the metal in the bath the weight a^7 has ceased to act on the handle side of the pivot and commences to act on the other side thereof, thereby aiding the workman to force the mold into the molten metal, this assistance being very useful, as the molten metal, by reason of its great specific gravity, will buoy up the mold with considerable force. The mold is thus pushed down by the movement of the lever until it reaches the bottom of the vessel containing the molten metal. During the above-described operation, while the mold is suspended in the blocks b^5 , the blocks are held so far apart by the handles of the mold that the pins b^3 are in the outer end of the slots b^2 , and the adjacent cam-surfaces on the lugs b^4 are not in contact, and the lugs b^4 incline upwardly from the horizontal plane passing through the center of the blocks b^5 , all as shown in Fig. 4. The mold having reached the bottom of the vessel containing the molten metal, the downward movement of the end a^6 of the lever is continued, forcing the lugs b^4 down toward and beneath a horizontal position, and tending thereby to force the blocks b^5 apart; but this tendency is resisted by the

handles of the mold, which is held together by the pressure of the metal against its sides. Consequently the adjacent surfaces of the lugs b^4 come together at that point of their surface nearest the center of the blocks b^5 , the pins b^3 sliding inward in the slots b^2 of the piece or arm b . During a further downward movement of the arm b the cam-surfaces of the lugs b^4 roll on or against each other, and as the points of greatest eccentricity of the cam-surfaces approach each other, the blocks, and with them the handles of the mold, will be forced apart, thus opening the mold, as shown in Fig. 5. The position of the parts when the mold is thus fully opened is clearly shown in Fig. 5, the mold being opened to its greatest extent when those parts of the adjacent cam-surfaces on the lugs b^4 which have the greatest eccentricity are in contact with each other, and are on or near the horizontal plane passing through the centers of the blocks b^5 , as shown. The flask now being opened and the metal having filled all its parts, it is now necessary that the mold should be closed while submerged in the molten metal. This can be done in two ways: First, the workman can reverse the movement of the lever A—that is, pull down or depress the handle end h —thereby raising the forward end a^5 and its attachments, and this upward movement of a^5 will reverse the movements of the blocks b^5 , and will draw the parts of the mold together, and by continuing the lowering movement of the handle end h the mold will be drawn out of the molten metal, and can then be swung around onto the stand D.

The movements of the parts thus far described are closely analogous to the ordinary toggle movement; but it is desirable in some cases that the closing of the mold should be effected as quickly as possible after it is opened, and that it should be held more tightly closed than can be done by the blocks b^5 alone. Therefore, instead of reversing—*i. e.*, raising—the forward end of the lever, which will require more time than the mold should be allowed to remain open, I prefer to continue the downward movement of the forward end of the lever a^5 and its attachments after the mold is fully opened and the parts are in the position shown in Fig. 5, and by this continued downward movement the lugs b^4 will be depressed still farther from the approximately-horizontal position in which they were when in contact, and as they turn on the handles b^7 as a pivot they will tend to separate; but this separation will be arrested by the pins b^3 striking against the outer ends of the slots b^2 in the arm b , and therefore a further downward movement will draw the lugs together, and consequently close the mold. It is apparent that if the handle end h were now depressed to raise the mold from the bath the mold would be again opened and the metal readmitted; but to prevent this reopening of the mold I employ the hooked dogs b^{10} , hereinbefore mentioned.

During the movements of the parts from the

position shown in Fig. 4 to that shown in Fig. 5 the tension of the spring s has kept the free ends of these dogs in contact with the blocks b^5 ; but at the point shown in Fig. 5 the spring has reached its normal position and will resist any further spreading of the dogs. During the movement of the end a^5 of the lever and its connections from the position shown in Fig. 5 to that shown in Fig. 6 the rounded ends of the dogs b^{10} strike on the top part of the mold, and, sliding outwardly thereon, are further spread apart against the tension of the spring s . When the mold has been completely closed by the downward movement above described, by which the mold was closed, the dogs b^{10} have been spread to such an extent that their hooks b^{11} can be forced by the spring s down over the edge of the mold and into the groove e , and the mold will be held tightly closed by said hooks. I prefer this downward movement for closing the mold, as it takes much less time than is required to close the mold by reversing the movements, as above described, and it is important to close the mold as quickly as possible after it is opened, as before stated.

I have described the downward movement of the end a^5 of the lever and its attachments as though it was intermittent, or step by step; but in actual operation this downward movement is continuous and rapid from the time the mold is over the bath until it has been submerged, opened and closed, the whole operation usually occupying not more than a fractional part of a second. As soon as the mold is closed and locked the handle end of the lever is pulled down, thus raising the mold from the bath, the mold being sustained and held closed during this upward movement by the hooked dogs b^{10} , and as soon as it has been raised sufficiently to disengage the friction-roller a^{15} from the slot in the standard c the lever is turned horizontally until the mold is over the stand D, on which it is deposited. As soon as the mold rests upon its stand the end a^5 of the lever is slightly depressed, so that the hooked dogs can be disengaged from the groove e ; then the handles b^9 of the bell-crank-levers b^8 are raised, swinging the hooks at the other ends of said levers from under the handles of the mold, when the end a^5 of the lever and its attachments can be lifted away from the molds; but before this is done the weight a^{13} should be again attached to the lever.

I have found in practice that the hooked dogs b^{10} are liable in some cases to allow the parts of the mold to move slightly apart when the mold is lifted, and that in consequence of such opening some of the metal in the mold escapes. To remedy this defect I use a locking-bar, D, (see Figs. 4, 5, and 6); but as this locking-bar is included in the subject-matter of another application, I have not described or claimed it herein, but refer for a full description thereof to such other application.

It is obvious that any suitable divided or

jointed mold having suitable handles may be used with the above-described apparatus, and I do not therefore limit myself to any particular form of mold.

5 In so far as relates to a mechanism in which the mold shall be reclosed by a continuation of the movement which opened it, it will be observed that this result is produced by what may be termed a "toggle-joint which passes 10 to the center"—that is to say, one in which the outward or spreading movement of the toggle-arms (which, in this case are lettered b') at first acts to push the two halves or parts of the mold apart, and then, after the point of greatest 15 distention is passed, or after their centers of motion pass below a line joining their pivotal points, (here lettered b'), such toggle-arms act to draw the two halves or parts of the mold together; but, as regards this feature, I do not 20 limit myself to any particular form or construction of toggle-arms or toggle-joint, and include herein the known substitutes and the 25 mechanical equivalents thereof, such as are adapted by a continuous movement to give first a spreading and then a closing effect; and when this construction and operation are adopted the presence of the locking mechanism described, or a suitable substitute therefor—such as will prevent the reopening of the 30 mold as it is lifted from the bath—becomes important. In other words, the lock should be such that the toggle-arms then cease to act as a toggle and become simply a means of lifting, and to this end any suitable lock may be employed adapted to do the work specified in 35 substantially the manner indicated.

I claim herein as my invention—

1. An apparatus for manipulating jointed or divided molds in casting metal, having in 40 combination a mechanism for taking hold of the opposite parts of said mold, mechanism for lowering and raising the mold, and mechanism for opening and closing the mold, substantially as set forth.

45 2. An apparatus for manipulating jointed or divided molds in casting metal, having in combination a mechanism for taking hold of the opposite parts of said mold, mechanism for moving the mold vertically and horizontally, and mechanism for opening and closing the mold, substantially as set forth.

50 3. An apparatus for manipulating jointed or divided molds in casting metal, having in combination mechanism for taking hold of the 55 opposite parts of said mold, mechanism for lowering and raising the mold, mechanism for opening and closing the mold, and mechanism for locking the mold when closed, substantially as set forth.

60 4. An apparatus for manipulating jointed or divided molds in casting metals, having in combination mechanism for taking hold of the opposite parts of the mold, mechanism for raising and lowering the mold, and mechanism for opening and closing the mold, all 65 constructed and arranged to be operated in lowering, opening, and closing the mold by a

continuous movement in one direction, substantially as set forth.

5. An apparatus for manipulating jointed or divided molds in casting metal, having in combination mechanism for taking hold of the opposite parts of the mold, mechanism for raising and lowering the mold, mechanism for opening and closing the mold, and mechanism 75 for locking the parts of the mold when closed, all constructed and arranged to be operated in lowering, opening, and closing the mold by a continuous movement in one direction, substantially as set forth.

80 6. The combination of the parts of a jointed or divided mold provided with suitable handles, two pivotally-mounted blocks provided with radial slots and a catch device for holding the mold-handles in said slots, and mechanism connected to said blocks whereby the mold may be raised and lowered and opened and closed, substantially as set forth.

85 7. The combination of the parts of a jointed or divided mold provided with suitable handles, a pair of pivotally-mounted blocks provided with radial slots and a catch device for holding the mold-handles in said slots, a pair of pivotally-mounted hooked dogs, and mechanism suitably connected with said blocks and 90 dogs, whereby the mold may be raised and lowered, opened and closed, and locked when closed, substantially as set forth.

95 8. The combination, with a bath of molten metal for the casting of metals by the submergence of a mold therein, and a lever mechanism for the raising and lowering of the mold, of a weight, a' , suitably arranged to counter-balance, wholly or in part, the weight of the mold before submergence, but to aid submergence as the latter takes place, substantially as 100 set forth.

105 9. The combination of the handles of a jointed or divided mold, the lever A , the arm b , pivoted to the end of said lever, and provided with horizontal slots, the cylindrical pieces b' , having radial V-shaped slots b'' , and provided with lugs b' , having cam-shaped ends, 110 said lugs b' being pivoted in the horizontal slots in the arm b , and the hooked bell-crank 115 levers b'' , substantially as set forth.

10. In combination with the halves or parts of a divided mold, and with a lowering mechanism for immersing the same in a bath of molten metal, a toggle-joint mechanism suitably arranged to open and reclose the mold without stopping the lowering mechanism, substantially as set forth.

11. In combination with the halves or parts of a divided mold, and with a lowering mechanism for immersing the same in a bath of molten metal, a toggle-joint mechanism suitably arranged to open and reclose the mold without stopping the lowering mechanism, and a locking mechanism for preventing the re-opening of the molds as they are lifted from the bath, substantially as set forth.

12. The combination of the lever A , the arm b , pivoted to the end of said lever, and

provided with horizontal slots b^2 and the hooked spring-dogs b^{10} , the cylindrical pieces b^5 , having radial V-shaped slots b^6 , and provided with lugs b^4 , having cam-shaped ends, 5 said lugs being pivoted to the arm b in the slots b^2 , the hooked bell-crank levers b^8 , and a divided or jointed mold provided with suit-

able handles, and having the groove or notch e , substantially as set forth.

In testimony whereof I have hereunto set my hand.
